SUCTION CLEANER

Vincent S. Belpedio, Bridgeport, Conn.

Application April 25, 1940, Serial No. 331,495

2 Claims. (Cl. 15—6)

The present invention relates to improvements in suction cleaners, and more particularly to means provided in relation to the suction opening for cooperating with the carpet or other surface being cleaned to subject it to a beating and brushing action for the purpose of loosening and removing dirt particles, so that the latter may be more effectually drawn into the cleaner by the suction. It is particularly proposed to provide in relation to beater means a motor driven rotary brush, such beater means being driven synchronously with the brush and arranged in such relation thereto that the carpet or other surface is subjected to a beating action slightly in advance of the rotary brushing action.

While beaters have been employed heretofore in suction cleaners their action has been such as to be injurious to the fibres of the carpet, this being due particularly to the fact that the main direction of the movement of the beaters is substantially at right angles to the carpet, with the result that the fibres are apt to become injured and the beating action caused the dirt particles to be forced downwardly through the carpet. It is an object of the present invention to provide beater means arranged in advance of the rotary brush and which move in an arc which is tangential to a plane disposed at an acute forwardly and upwardly inclined angle to the surface of the carpet, to the end that the beaters will engage the sides of the carpet fibres and will tend to loosen the dirt particles and deflect them toward the rotary brush, so that they will be most effectually removed by the suction. It is further proposed to arrange the direction of the movement of the beaters during their beating action in opposition to the forward direction movement of the cleaner, so that the beater action will not tend to oppose this movement, but will in fact assist it thereby increasing the ease with which the cleaner may be operated.

A further object is to provide rotary brush means having a series of tuft strips progressively offset with respect to each other axially of the brush, so that the carpet is not simultaneously engaged across the full width of the rotary brush, whereby a more even and uniform cleaning results. It is proposed in combination with such brush means to provide a plurality of beaters adapted to alternately engage the carpet in synchronism with the engagement by the brush strips, so that the beating action is substantially uniformly timed with the engagement of the carpet by the brush strips. A further ob-

ject is to provide a beater mechanism which may be economically manufactured and assembled, and which may be incorporated in standard types of suction cleaners without materially altering their design. In this connection it is proposed to drive the beater means through a drive connection between the rotary brush and the beater means, such rotary brush being driven by the usual belt drive from the electric motor.

With the above and other objects in view, embodiments of the invention are shown in the accompanying drawing, and these embodiments will be hereinafter more fully described with reference thereto, and the invention will be finally pointed out in the claims.

In the drawing:

Fig. 1 is a view in vertical section, longitudinally through the cleaner, the forward portion of the view, showing the beater and rotary brush mechanism, being taken along the line A—A of Fig. 2.

Fig. 2 is a transverse sectional view, taken along the line B—B of Fig. 1, the rotary brush being shown partially in vertical section and partially in elevation.

Fig. 3 is a perspective view of one of the beater elements.

Fig. 4 is a longitudinal vertical sectional view of the forward end portion of a suction cleaner according to a modified form of the invention, in which the beater elements are provided both in front and in back of the rotary brush, this view being taken along the line C—C of Fig. 5.

Fig. 5 is a transverse sectional view taken along the line D—D of Fig. 4.

Similar reference characters indicate corresponding parts throughout the several figures of the drawing.

Referring to the drawing, and more particularly to Figs. 1 to 3 thereof, the suction cleaner according to the illustrated embodiment of the invention shown therein comprises a casing indicated generally as 10, having the usual wheel supports 11 at each side, and provided with a nozzle portion 12 extending across the forward end thereof and a dome-shaped motor housing portion 13 in which the motor 14 is mounted upon a plate 15, this motor being provided with a downwardly projecting shaft 16 having a drive belt engaging groove 17 at its lower end and suction fan blades 18 adjacent the motor disposed in a fan chamber 19 formed by the separate bottom wall section 20 secured to the casing, the fan chamber having connected at its rearward end

the dust collecting bag 21. The shaft 16 extends through an opening 22 in the wall 20 which provides communication between the nozzle portion and the fan chamber. Upon the lower edge of the nozzle portion of the casing there is detachably secured a bottom plate 23 having an opening 24 constituting the suction mouth of the nozzle, and within which the action of the rotary brush and beater elements takes place, as will presently more fully appear. The bottom plate 23 is retained in place by a spring latch 25, which upon being released from the lip 26 of the bottom plate permits removal of the plate. In addition to the wheels 11 the cleaner is supported upon the usual yieldably mounted rear wheels 27. It will be understood that the cleaner parts above described are those employed in known types of suction cleaners, being shown herein simply by way of example, and that these parts may be varied as desired.

The rotary brush element is made up of a series of axially aligned cylindrical brush roller sections, each consisting of a cylindrical wall 28 provided with an integral end wall 29 at one end, the other end having a flanged disc 30 inserted and rigidly secured therein, preferably by welding. In the illustrated embodiment four such sections are employed, although it will be understood that this number may be varied if desired. In the particular arrangement employing four sections the two sections at each side of the center are rigidly secured together in spaced relation by a bearing shaft 31, having a flange 32 at one end rigidly secured to the disc 30 of one of the sections, preferably by welding, and having at its other a shouldered stud 33 engaged in the disc 30 of the other section and rigidly secured by riveting over, as at 34. These shafts 31 are eccentrically disposed for the purpose of driving the beater elements, as will presently more fully appear, and the shaft at one side is preferably diametrically opposite to the shaft at the other side with respect to the central axis of the rotary brush, as shown clearly in Fig. 1.

The end walls 29 of the two intermediate sections are rigidly secured together by a pulley wheel 35, the stud shaft ends 36 of which project through the end walls 29 and are rigidly secured by riveting over, as at 37.

The end walls 29 of the end roller sections are provided with flanged bearing cups 38 in which a recessed cone bearing element 39 is engaged, this being preferably formed of self-lubricating material, and which is adapted to be adjustably engaged by the cone bearing screw 40 mounted in each end of the casing. These screws as shown are each mounted in an eccentric nut 41 rotatably engaged in a bearing opening 42 in the casing and frictionally retained in place by a friction spring washer 43. The eccentricity of the nuts 41 is such that upon turning them in the bearing openings 42, the height of the cone bearing screws with respect to the floor may be adjusted to vary the degree of engagement of the brush with the floor, as well as the relative positions of the beater elements with respect to the rotary brush, and as will hereinafter more fully appear.

Each of the brush sections is provided with longitudinal circumferentially spaced grooves 44, in each of which a brush strip 45 is engaged, the position of the brush strips of the several sections being progressively offset longitudinally of the rotary brush, so that the engagement of

the brush strips of each section is slightly in advance of the succeeding section. The rotary brush is driven from the motor by means of a belt 46 extending over the shaft 16 and the pulley 35.

The beater elements, one of which is disposed in relation to each half of the rotary brush, each consists of a beater bar portion 47, having a pair of curved supporting arms 48 extending upwardly therefrom near each end, and provided with axially aligned tubular bearing portions 49 spaced from each other for receiving a driving link, as will presently more fully appear, and provided with bearing arms 50 having axially aligned bearing portions 51, which are engaged in bearing fixtures 52 integrally formed upon the underside of the nozzle portion 12 of the casing, and having bearing pins 53 engaging the bearing portions 51. The axis of the bearing pins 53 is preferably in the vertical plane of the axis of rotation of the rotary brush, and the beater elements extend about the forward side of the rotary brush, so that the direction of movement of the beater bar portions 47 with respect to the surface of the carpet is tangential to a plane disposed at an acute forwardly and upwardly inclined angle to the surface of the carpet, and as indicated by the arrow in Fig. 1. The beater elements are each adapted to be driven by a link 54 engaged at one end with the eccentric shaft 31 and having its other end engaged between the tubular bearing portions 49, a pivot pin 55 being engaged through these bearing portions to pivotally connect the link.

As shown clearly in Fig. 1 the eccentric shafts 31 have their axes diametrically opposed with respect to the axis of rotation of the brush roller, so that one beater element moves downwardly into beating engagement with the carpet while the other beater element moves upwardly, and the point of engagement of one beater element is thus substantially synchronized with the engagement of the carpet by the circumferentially offset brushes at each side of the center of the rotary brush, so that the combined beating and brushing action is uniform across the full width of the cleaner. The manner in which the beaters engage the carpet surface in an arc tangential to an acute angle forwardly of the rotary brush is such that the beat up particles of dirt are deflected toward the brush, the brushing action following the beating action in such close relation that the carpet fibres are disposed by the beaters in the most effective position to be engaged by the brushes. This action is further enhanced in that the suction action lifts the carpet slightly at the point where the nozzle opening 24 engages the carpet, so that the carpet is supported upon an air cushion as it is being beaten. Inasmuch as the direction of the movement of the beater elements with respect to the floor is substantially in opposed relation to the forward movement of the cleaner the beater action will not tend to resist this forward movement, but will in fact assist it.

In Figs. 4 and 5 I have shown a modification in which the beater elements are provided both in front and in back of the brush, these being substantially similar to the elements, as shown in the first embodiment. The rearward units have their bearing arms 50 inwardly offset with respect to the bearing arms of the forward elements, so that they may engage between the bearing fixtures 52, the front and rear beater

elements both being secured by a pivot shaft 53^a extending through the two bearing fixtures 52. The drive links 54^a and 54^b of the forward and rearward beater elements, are both connected to the same eccentric shaft 31, the link 54^a having a split bearing portion 56 within which is engaged the bearing portion 57 of the link 54^b. In consequence of this drive connection the forward and rearward beater elements will have alternate beating action, the rearward unit moving away from the carpet surface as the forward unit moves toward it. While only one pair of forward and rearward beater elements is shown at one side of the cleaner, it will be understood that the arrangement is duplicated at the other side, except that the beater elements at each side preferably have alternate action as in the first embodiment. The action of the rearward beater in addition to that of agitating and loosening any dirt particles which may remain after engagement by the forward beaters and the brushes, is to compensate for the beating action of the forward beaters in restoring the rug fibres to their normal position, as well as to compensate for the brushing action which tends to bend the fibres downwardly in one direction.

While I have shown the beater elements arranged in pairs it will be understood that either a single beater or three or more may be employed.

It will also be understood that other types of rotary brushes may be employed, as for instance, one with spirally arranged tufts.

I have illustrated and described preferred and satisfactory embodiments of the invention, but it will be understood that changes may be made therein, within the spirit and scope thereof, as defined in the appended claims.

Having thus described my invention, what I claim and desire to secure by Letters Patent is:

1. In a suction cleaner having a casing pro-

vided with a nozzle mouth arranged to pass over the carpet surface or the like to be cleaned, a rotary brush mounted in said nozzle mouth, a beater element comprising an arm pivotally mounted at its upper end in said casing extending downwardly in spaced relation about the periphery of said rotary brush at one side and having a carpet engaging surface at its lower end adapted to move in an arc about the pivotal mounting of said beater element, said arc being tangential to a plane inclined at an acute angle to the plane of the surface to be cleaned, and a driving link pivotally connected to said arm intermediate its upper and lower ends and pivotally connected eccentrically to said rotary brush adapted to oscillate said beater element as said brush is rotated.

2. In a suction cleaner having a casing provided with a nozzle mouth arranged to pass over the carpet surface or the like to be cleaned, a rotary brush mounted in said nozzle mouth, a pair of beater elements pivotally mounted in said casing upon a common axis and in the same vertical plane with the axis of said rotary brush, one of said beater elements being forwardly and the other rearwardly of said rotary brush, each having a carpet engaging surface adapted to move in an arc about the pivotal mounting of said beater elements, said arcs being respectively tangential to planes inclined at an acute angle to the plane of the surface to be cleaned, one of said planes being inclined forwardly and upwardly and the other being inclined rearwardly and upwardly, and a pair of driving links pivotally connected eccentrically to said rotary brush upon a common axis, and respectively pivotally connected to said beater elements at points intermediate their pivotal mountings and their carpet engaging surfaces adapted to oscillate said beater elements.

VINCENT S. BELPEDIO.
